(57) **CLAIM**

The ornamental design for a cigar package, as shown and described.

DESCRIPTION

FIG. 1 is a first perspective view of a cigar package in a closed, unfilled configuration in accordance with the claimed design;

FIG. 2 is a front elevational view of the cigar package of FIG. 1 in the closed, unfilled configuration;

FIG. 3 is a rear elevational view of the cigar package of FIG. 1 in the closed, unfilled configuration;

FIG. 4 is a top plan view of the cigar package of FIG. 1 in the closed, unfilled configuration;

FIG. 5 is a bottom plan view of the cigar package of FIG. 1 in the closed, unfilled configuration;

FIG. 6 is a first side elevational view of the cigar package of FIG. 1 in the closed, unfilled configuration;

FIG. 7 is a second side elevational view of the cigar package of FIG. 1 in the closed, unfilled configuration, the second side being opposite the first side;

FIG. 8 is a second perspective view of the cigar package of FIG. 1 in an open, and unfilled configuration; and,

FIG. 9 is a third perspective view of the cigar package of FIG. 1 in a closed, filled configuration.

The broken lines in the drawings illustrate portions of the cigar package that form no part of the claimed design.

1 Claim, 6 Drawing Sheets
